APPARATUS FOR LIFTING LIQUIDS

Frederick E. Key, St. Louis, Mo.

Application July 5, 1935, Serial No. 30,007

4 Claims. (Cl. 103—239)

This invention relates to apparatus for lifting liquids by gas pressure and has particular utility in pumping wells and especially oil wells.

5 An object of this invention is to provide efficient means for lifting liquids by gas pressure and for elevating liquids a great height by means of comparatively low pressure.

Another object of this invention is to provide 10 means for lifting liquids by gas pressure which will conserve pressure and obtain maximum work out of the energy required.

Another object is to provide a liquid lifting 15 means utilizing a gas under pressure so arranged and adapted as to conserve the volume of gas required in its operation.

Another object of the invention is to provide 20 means for elevating liquids which will efficiently lift liquids at a comparatively low rate of flow, whereby, when applied to an oil well, for example, the well may be pumped continuously and, at the same time, efficiently. By taking the oil from the well continuously, as fast as it flows in, back pressure is prevented, thus enhancing the production. Also the tendency of sand to plug the 25 well is reduced.

Another object of the invention is to provide 30 liquid lifting means suitable for well pumping without the use of moving mechanical means such as sucker rods and piston within the well, to eliminate difficulties which attend such use.

Another object is to provide means for pumping 35 an oil well which will agitate the oil less than conventional methods, to prevent freeing gaseous components. A further object is to provide apparatus for this purpose which may be readily flushed with a solvent to dissolve paraffin or gum deposit without pulling the apparatus from the well.

In oil wells, there is usually a quantity of water 40 present and the oil and water stratify, with the oil on top. By conventional methods it is necessary to lift all of the water above the level of the pump inlet before the oil can be reached. By pumping from the top of the liquid body the oil may be evacuated without the use of power to 45 lift the water. An object of this invention is to provide means for pumping a well from the top of the liquid body at a range of levels.

Other and specific objects will be apparent 50 from the following detail description taken in connection with the accompanying drawings.

Fig. 1 is a diagram of apparatus embodying and utilizing the invention;

Fig. 2a is a view showing details of construction 55 of the upper part of a device embodying the invention in a well; Fig. 2b is a view showing details of construction of the lower part of the device and is a continuation of the view shown in Fig. 2a;

60 Fig. 3 is a diagram of a pneumatic system of

control including valves and valve operating and timing mechanism;

Fig. 4 is a detail, partly in section of the two-way valves included in the system shown on Fig. 3;

Fig. 5 is a detail, partly in section of pressure regulator valves included in Fig. 3;

Fig. 6 is a diagram of a modification in which the well pressure is used to operate the system; and

Fig. 7 is a diagram of a further modification in which subatmospheric pressure alone is used.

A plurality of superimposed chambers, 1, 2, 3, 4, 5, 6, 7, 8, 9 and 10, are connected alternately to gas pressure lines A and B, the odd numbered 15 chambers being connected with A and the even numbered chambers being connected with B. The bottom chamber 1 has a port 11 communicating with a body of liquid in which that chamber may be immersed. The intermediate and top 20 chambers each has a tube 12 extending downwardly into and open near the bottom of the next succeeding chamber. A discharge pipe 13 extends downwardly into and opens near the bottom of the top chamber 10, discharging prefer- 25 ably at atmospheric pressure.

Means are provided for producing gas pressures of different magnitude in the lines A and B respectively and for reversing the relationships. That is to say, a superatmospheric pressure first may be provided in line A while a subatmospheric pressure is provided in line B, after which the pressures are reversed in the two lines. Two-way valves 14 and 15 are provided for the lines A and B, respectively, each opening its line 30 selectively to a line 16, leading to a source of gas pressure and a line 17 leading to a suction device, or through a valve 18 to atmosphere.

Preferably, means is provided for connecting the lines A and B, illustrated diagrammatically 40 as a valve 19.

The valves 14, 15 and 19 may be operated by timing mechanism, to produce successive cycles, each comprising the following phases: I. In which the valve 14 is operated to open and then 45 to close the line A to pressure, while the valve 15 opens and then closes the line B to suction; II. In which the valve 19 connects and then disconnects the lines A and B; III. In which for a period, the line B is open to pressure and the line A is open 50 to suction; and IV. In which the lines A and B are again connected.

The result of the operation is that liquid will be lifted simultaneously from alternate chambers into the complementary chambers respectively. 55

The ports 11 and the tubes 12 are provided with check valves 20 to prevent back flow.

The tube 13 is provided with a float valve 21, the details of which are shown in Fig. 2a. This valve is so constructed as to prevent the gas un- 60

der pressure from blowing by after the top chamber has been drained below the bottom of the tube 13.

The foregoing is a brief description of the embodiment as specifically shown in the drawings, while the essential features of the invention are included in the appended claims. The following supplemental description will assist in understanding and practicing the invention.

10 The superimposed chambers 1 to 10, may be of a number and construction to suit the purpose to which they may be applied. For example, when used in a well they may be of ordinary tubing 22, of a size which enables them 15 to be inserted readily in a well casing 23.

The diameter of the chambers, of course, may be varied to suit requirements. The length will depend upon the depth of the liquid in which the line of chambers may be immersed and the 20 pressure to be used. If chambers 100 feet in length are used, making a total maximum lift of nearly 200 feet from the bottom of one chamber to the top of the next, a differential pressure of approximately 100 pounds per square inch is 25 required.

The pressure line 16, connectible selectively with the lines A and B, taps a source of pressure, such as a storage tank 24, supplied by a compressor P, while the line 17 may be connected 30 with the intake of the compressor, or open to atmosphere, as indicated by the valve 18.

The closed circuit, using pressure on one side and suction on the other, has advantages and especially in pumping oil. It conserves power 35 and also conserves, when essential, the gas used in the system. In pumping oil a gas other than air should be used, otherwise an explosive mixture will result and present a hazard. Thus, if a gas having an intrinsic value is employed, the 40 closed system results in conserving the gas.

45 The valve 19, or equivalent means for connecting the lines A and B, is provided also as a measure of economy and not of necessity, since the chambers may be exhausted directly to atmosphere by the valves 14 and 15. But whether air or another gas is used, energy is conserved by first equalizing the pressure in the lines A and B by their connection, rather than exhausting the pressure in the line at the end of a pressure phase.

50 Details of a typical installation of those parts of the apparatus inserted in a well are shown in Fig. 2a and 2b. The construction is such that the device may be readily assembled and placed 55 in the well. The chambers are formed of tubing 22 connected by suitable fittings 26 to which are attached plates 27 separating the chambers, later described in more detail. The lines A and B are contained within the tubing and open to the appropriate chambers.

55 A fitting 26 is secured to the bottom of the tube forming the chamber 1. It is internally threaded at both ends and has a conical seat 28 to receive an annular block 29, which is bored to form the port 11 and which supports a housing 30 for a check valve 20. The block 29 is held on its seat by a jam nut 31 having external threads to engage corresponding internal threads on the fitting 26. A strainer 32 may be supported by the fitting 26 as shown.

70 The plates 27 separating the chambers are conical in form to fit on conical seats 28 in the fittings 26. Each is secured in position by a jam nut 31. Each of the plates 27 is bored and threaded to receive and support a tube 12 which

opens into the chamber above the plate and extends downwardly into the chamber below the plate. The plate 27 forming the top wall of the chamber is bored and threaded to receive the lower end of the line A in such a manner that the line is open into the chamber 1, and the plate forming the top wall of the chamber 2 likewise is bored and threaded to receive the lower end of the line B. The last named plate 27 is also bored to pass the line A and is provided with a packing gland 33. The upper plates 27 are each bored to pass the lines A and B and provided with packing glands 33 as clearly shown in the drawing.

As previously described, the lines A and B open 15 into alternate chambers. In the chambers above the second this opening is provided by means of a fitting 34 on the appropriate line and having a port 35 in its wall situated at the upper end of the chamber.

20 A housing 36 for a check valve 20 is threaded on the end of each of the pipes 12.

The casing head includes a block 37 in which the top of the tubing 22 is threaded and thereby supported. The block 37 rests upon an annular flange 38 threaded to the casing 23. A cap 40 engages an annular surface on the top of the block 37 and the block 37, flange 38 and cap 40 are held together by bolts 41 to seal the casing. The cap is bored and threaded to support the 30 discharge tube 13 which extends downwardly into the top chamber and also the pipe 13a forming a part of the discharge conduit and leading to storage. The cap 40 is also bored to pass the 35 lines A and B, which are packed with glands 33. 35

The float valve 21 on the bottom of the tube 13, as specifically shown, includes an annular seat 41 with ports 42 opening into the tube 13 from the top chamber 10. A valve member 43 carried by a sleeve 44, to which is secured a float 45, is adapted to reciprocate vertically on the tube 13 and when the level of liquid in the chamber 10 falls below a predetermined level to cover and close the ports 42. A collar 46 is secured to the pipe 13 to limit the uppermost position of the sleeve 44. It will be understood that the chamber 10 will empty before the other chambers because the liquid need be forced to only approximately the top of this chamber, while with the other chambers the maximum lift, from the bottom of one chamber to the top of the next, is nearly twice as great. The timing of the cycles and the pressure will be arranged so that the other chambers will not be emptied to a point below the bottom of the respective pipes 12. Thus, with the float valve 21, and the timing and pressure properly arranged, no gas in the system need be lost except through absorption.

60 Valve and timing mechanism for operating the system may be of widely different forms. The timing system may be operated mechanically, electrically, or pneumatically, as desired and as most convenient. A preferred system of pneumatically operated valves is shown diagrammatically in Fig. 3. The system illustrated in that figure operates to produce the four-phase cycle heretofore described. The lines A and B may be connected by means equivalent to that of the single valve 19 but arranged in such a way that 65 the entire cycle may be controlled by two lines. The valves 14 and 15 are adapted to open the lines A and B respectively, either to line 16, connected with the pressure tank 24, or to a common line 47 which may be connected by valves 48 and 70 75

49, in parallel, to the line 17 leading to a suction receiver 50.

The valves 14 and 15 are each operated by a diaphragm device 51 constructed and arranged as shown in Fig. 4. Each valve includes a lower seat 52 and an upper seat 53 for valve members 54 and 55 respectively, both carried by a stem 56 secured to a flexible diaphragm 57 and normally held in upper position by a spring 58. The arrangement is such that in the absence of pressure on the diaphragm 57 the upper valve member 55 will seat closing the line 16, and lower valve member 54 will open the line 47. Pressure upon the diaphragm 57 will depress the valve stem and seat the valve member 54, thus closing the line 47 and opening the line 16.

The construction of the valves 48 and 49 is shown in detail in Fig. 5. Each includes valve members 59 carried by a stem 60 normally held in uppermost or closed position by a spring 61 and adapted to be pressed downwardly to open position by pressure upon a diaphragm 62.

The valves 14 and 48 are controlled by a single line 63 and the valves 15 and 49 are controlled by a single line 64. The lines 63 and 64 are connected to and controlled by a timing device 65. This device is one available commercially and need not be described in detail. It consists essentially of a clock mechanism rotating a pair of cams, operating valves respectively which are adapted to introduce pressure into the lines 63 and 64.

The pressure for the timing mechanism 65 is received from a line 66, connected to the pressure tank 24 and having therein a filter 67 and a regulating valve 68. The filter may be of known commercial construction and the regulating valve 68 may be also of known commercial construction, preferably adapted to supply pressure at approximately 20 pounds per square inch. It will now be understood that the construction and arrangement of the valves 14 and 15, as controlled by the mechanism 51, is such that with pressure on their respective diaphragms they will open their line, A or B, to the pressure line 16 and upon release from pressure they will open their lines to the common line 47, which may also be connected through either of the valves 48 and 49 to the suction line 17.

The timing mechanism is arranged to produce a cycle containing the four phases as previously described but which may be described more in detail in connection with the specific mechanism, as follows:

Phase I.—Pressure is placed on the line 63 and is released on the line 64; valve 14 thereby opens line A to line 16; valve 15 opens line B to line 47, which is opened by valve 48 to suction line 17, while valve 49 is closed; and, therefore, the line 60 A is open to pressure, and the line B is open to suction.

Phase II.—Pressure is released on line 63 while it remains released on line 64, thus both lines A and B are open only to line 47 while the valves 48 and 49 are both closed and the lines A and B are thereby connected.

Phase III.—Pressure is introduced into line 64 while pressure remains released in line 63; the line A thereby remains open to line 16, which through valve 49 is open to suction line 17, valve 48 being closed, and the valve 15 opens line B to pressure in line 16; and, therefore, the line A is open to suction and the line B open to pressure.

Phase IV.—Pressure is released on both control lines 63 and 64, thereby connecting lines A

and B through line 47 as previously described in connection with Phase II.

It will be understood that the cycle just described will be repeated in succession under the control of the timing mechanism 65.

To provide pumping from the top of the liquid body, ports 69 and check valves 70 may be provided in some or all of the chambers, if suction is not put on the chambers, that is, if superatmospheric pressure is used on one side of the system and atmospheric pressure is used on the other side. These ports permit lifting of liquid from their levels rather than from the bottom of the well, or the level of the port 11. As specifically illustrated in Fig. 1, ports 69 are provided in the chambers 1, 3 and 5. They function in the manner presently described. Assuming that there are ten chambers each 100 feet long, the device will reach to a depth of 1000 feet with the port 11 at that level and in the absence of the ports 69 liquid would be pumped from that point. Assuming that oil is standing in the well casing at approximately the 500 foot level as indicated by the line marked "Liquid level" with 200 feet of oil leaving 300 feet of water above the port 11, oil will flow through the port 69 in the chamber 5 until it fills the chamber, in the absence of pressure in the line A, and the chamber 5 will be filled very quickly. The flow will be at a much more rapid rate than flow upwardly through the pipe 12, which extends into the chamber 4, under influence of pressure in the line B. If the chamber 4 is filled with water and the chamber 5 is being filled through its port 69 with oil, there will be a relatively small flow of water from the chamber 4 into the chamber 5. The proportion depends, of course, upon the head pressure of the liquid in the well, the amount of pressure exerted through the pipe B and the relative size of the openings in the pipe 12 and the port 69. Under ordinary circumstances these factors will be so proportioned that only a small amount of water will be lifted with the oil.

If the fluid line in the well drops below the port 69 in the chamber 5 the major portion of the liquid lifted then will be that which enters the system through the port 69 in the chamber 3. It is contemplated, of course, when the ports 69 are used that the system will be operated at such a rate that it will evacuate the oil only, with, of course, a small percentage of liquid from the lower chambers as suggested. It will be obvious, of course, that ports 69 may be placed in the other chambers when necessary or desirable. The advantages in the use of the intermediate ports 69, in connection with pumping oil wells, will be obvious. Where there is water in the well the oil will rise to the top and form a layer from which layer the lifting may be accomplished. It will be unnecessary to exhaust the water in the well in order to raise the oil and only a small amount of water will be pumped incidentally with the oil. The system will accommodate itself to a range of levels, with the major portion of the liquid comprising that flowing through the highest immersed port 69. While advantages result from the use of the ports 69 and valves 70, their use will not be indicated universally, and especially where suction is employed on one side of the system. Accordingly the use of these members is optional.

A pressure relief valve PR shown in Fig. 1, in connection with the tank 24, may be provided especially where the closed system is used in pumping oil wells. Where suction is used volatile

compounds in the well may increase the pressure in the system, if not relieved, beyond the desired range.

Frequently, an oil well will have a pressure sufficient to operate this system, while insufficient to flow the well by conventional methods. Fig. 6 illustrates an application of the system to utilize the well pressure as a source of energy. The pipe 16 in this case is connected with the well casing 5 at the cap 40 by a line 71. The valves 14 and 15 may be operated as previously described. In this case there is no necessity for connecting the two lines A and B. When operated as shown in this figure one of the lines A or B will be connected with the gas pressure in the well while the other line will be open to atmosphere.

As shown in Fig. 7, the system may be operated with atmospheric pressure on one side and with suction on the other. In that case the chambers 10 to 19 will be relatively short and suction will be applied intermittently also to the discharge pipe 13. As shown in the diagram this is accomplished by connecting a chamber 72 with the pipe 13 and connecting the line A with the chamber 25 72 by a line 73. A check valve 14 covers a port 75 in the chamber 72, whereby the chamber may empty by gravity at atmospheric pressure when atmospheric pressure is restored in line A. In this embodiment a check valve 20a instead of a 30 float valve should be provided in the discharge pipe 13.

In practicing the method and in the operation of the apparatus the chambers are lowered in a well, if it is to be used for pumping a well, until 35 the lower chamber at least is immersed in the liquid to be lifted. This is essential, otherwise the liquid will not flow through the port 11 sufficiently to fill the chamber 1. Of course, if suction is used, this will be sufficient to raise the 40 liquid in the bottom chamber 1 above the level in the well, and the chamber need not be fully immersed. In order to provide complete immersion of the bottom chamber 1, it may be shorter than the others, if its diameter is increased to provide 45 the same capacity.

The device should be primed by filling alternate chambers and the process may then be initiated. A line 76 connectible with the line A by a valve 77, Fig. 1, is provided for priming the 50 system through the line A.

Pressure through the line A will force the liquid from the odd numbered chambers to the even numbered chambers, respectively, then pressure will be applied through the line B to the 55 even numbered chambers. Thus the liquid is raised step by step causing an intermittent flow through the discharge pipe 13.

Pumping equipment for oil wells is subject to 60 deposits of paraffin or gum, requiring the equipment to be removed from the well for cleaning. With equipment embodying this invention a solvent for the deposit may be introduced through the priming pipe 76 and the apparatus thus cleaned in a simple and economical manner.

Various advantages of the specific steps have 65 been pointed out in the foregoing description, and especially that in connection with the use of the suction line and the equalization of pressure between the two lines A and B between principal 70 phases in the cycles.

As clearly indicated in the foregoing specifica-

tion, parts of the invention may be used without the whole and various changes may be made in the details of construction, within the scope of the appended claims, without departing from the spirit of this invention. In fact, apparatus differing very widely may be employed in practicing the method while retaining many of its advantages.

I claim:

1. In apparatus of the character described, 10 including an upper and a lower tubular chamber adapted to be inserted in a well and a plurality of vertical tubes inside said chambers, a cylindrical connecting member having its ends threaded respectively to the adjacent ends of the 15 chambers, a conical seat intermediate said threaded connections, a rigid conical wall member on said seat, a jamb nut threaded interiorly in said connecting member and positioned to hold said wall member on said seat, orifices in said wall member, and means for anchoring said tubes to said wall.

2. In apparatus of the character described the combination comprising a pair of tubular members adapted to be connected end to end and inserted in a well, a tube extending longitudinally through such tubular members, and means to form a connection for said tubular members and to form a wall dividing said members into separate chambers respectively including a thimble 20 having its ends threaded respectively to the adjacent ends of the tubular members, a conical seat in the thimble intermediate said threaded connections, a rigid conical wall member on said seat and having an orifice to pass said tube, and a jamb nut threaded interiorly in said thimble 25 and positioned to hold said wall member on said seat.

3. In apparatus of the character described the combination comprising a pair of tubular members adapted to be connected end to end and inserted in a well, and means to form a connection for said tubular members and to form a wall dividing said members into separate chambers respectively including a thimble 40 having its ends threaded respectively to the adjacent ends of the tubular members, a conical seat in the thimble intermediate said threaded connections, a rigid conical wall member on said seat, and a jamb nut threaded interiorly in said thimble 45 and positioned to hold said wall member on said seat.

4. In apparatus of the character described the combination comprising a pair of tubular members adapted to be connected end to end and inserted in a well, a tube extending through one of said tubular members and adapted to open into the other tubular member, and means to form a connection for said tubular members and to form a wall dividing said members into separate 60 chambers respectively including a thimble having its ends threaded respectively to the adjacent ends of the tubular members, a conical seat in the thimble intermediate said threaded connections, a rigid conical wall member on said seat, and a jamb nut threaded interiorly in said thimble 65 and positioned to hold said wall member in said seat.
